Inventor
MILTON TIBBETTS.

UNITED STATES PATENT OFFICE

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN

SPRING COVER

Application filed October 26, 1928. Serial No. 315,158.

This invention relates to motor vehicles and more particularly to covers for the springs thereof.

An object of the invention is to provide a spring cover for the protection of the spring from dust, mud, water and other extraneous material which would have an injurious effect thereon.

Another object of the invention is to provide a spring cover adapted to retain lubricants within and between the portions of the springs which slide or move one on another.

Another object of the invention is to provide a sectional spring cover designed to permit unrestricted movement of the spring.

Yet another object of the invention is to provide a spring cover having a lining removable with the cover.

A further object of the invention is to provide a sectional spring cover having a separate lining for each section arranged to telescope with one of the adjacent sections.

A further object of the invention is to provide a sectional metallic spring cover having a lining permanently secured to the inner wall of each section and provided with means whereby the cover may be easily and quickly applied or removed.

Still a further object of the invention is to provide a sectional metallic spring cover which is highly efficient in operation and yet of marked simplicity as a whole and in respect to each of its component parts, so that its manufacture may be economically facilitated both as to parts and their assembly.

Other objects of the invention will appear from the following description taken in connection with the drawings, which form a part of this specification, and in which:

40 Fig. 1 is a side elevation of a half elliptic spring illustrating the invention as applied;

Fig. 2 is an enlarged side elevation of a spring with the cover applied, the cover being shown in section, and a portion of the spring being broken away;

Fig. 3 is an enlarged top plan view of the spring with the cover applied, the cover being shown in section, and a part of the spring being broken away;

Fig. 4 is a cross sectional view substantially on line 4—4 of Fig. 2;

Fig. 5 is a top plan view illustrating a modified form of the invention, and

Fig. 6 is a cross sectional view of the modified form.

Referring to the drawing for more specific details of the invention, 10 represents generally a leaf spring of the type well known in the art as a semi-elliptic spring. The 60 spring shown is built up from a main or master leaf 11 provided at its ends with eyes 12, and a series of super-imposed leaves 13 and 14 arranged above and below the master leaf and secured thereto and to each other by a 65 center bolt 15.

Positioned on the spring on each side of the center bolt is a plurality of sleeves or jackets 16. As shown, the jackets are in graduated sizes, each gradually decreasing in 70 cross section so that when adjusted to the spring the assembly conforms substantially to the general contour of the spring, when in an unsprung position. The jackets which are formed from thin sheet metal are longitudinally split so that they may be clipped over the spring and the split edges are turned outwardly to provide flanges 17 in which are positioned transverse bolts 18 for securing the jackets on the spring.

75 The jackets 16 are provided with linings 19, preferably waterproofed felt. As shown, the linings are cut and shaped to conform to the jackets and the flanges thereon, and are secured in the jackets by rivets 20, though they may be cemented or otherwise secured in position. They are relatively thick and are positioned in the jackets so that one end of a lining is spaced from the adjacent end of the jacket in which it is secured as indicated at 80 21 and the opposite end extends outwardly beyond the jacket as indicated at 22. The waterproofing is indicated at 19'.

85 The jackets are arranged on the spring in abutting relation with the lining in one jacket telescoping one of the jackets immediately adjacent and abutting the lining therein. The abutting ends of the linings are encased by the jackets, and fillers 23 are inserted at the top and bottom. The fillers 23 are substan- 100

tially wedge shaped members which may be loosely placed in position or permanently secured to the lining and are adapted to fit the linings snugly to the springs.

5 Figs. 5 and 6 illustrate a modified form of the invention. In this modification the jacket is formed in two corresponding parts hinged together so that the cover may be readily applied or removed. As shown, the jacket 10 is divided longitudinally as at 24 and a strip of fabric 25, preferably waterproofed, is positioned on the interior of the jacket and riveted to the two parts as at 26 to provide a suitable hinge. The fabric 25 not only provides 15 a hinge whereby the jacket may be easily and quickly removed from the spring together with its lining, but serves to seal the joint between the two parts of the jacket.

Although the invention has been described 20 in connection with certain specific embodiments, the principles involved are susceptible of numerous other applications that will readily occur to persons skilled in the art. The invention is therefore to be limited only 25 as indicated by the scope of the appended claims.

Having thus described the various features of my invention, what I claim as new and desire to secure by Letters Patent is:

30 1. A spring cover comprising a metallic jacket, a lining secured in the jacket, said lining spaced from one end of the jacket and extending beyond the other end.

35 2. A spring cover comprising a plurality of jackets, each having a lining secured therein spaced from one end and extending beyond the other end, said jackets arranged in abutting relation with the lining in one telescoping with another.

40 3. A spring cover comprising a split metallic jacket having a gradually decreasing cross section and a lining secured to the jacket, the exterior of the lining being waterproof.

45 4. A spring cover comprising metallic jackets arranged in abutting relation, each jacket being gradually reduced in cross section and split longitudinally, and a lining secured to each jacket, the exterior of the lining being waterproof.

50 5. A spring cover comprising metallic jackets arranged in abutting relation, a lining secured to the inner wall of each jacket, the linings being arranged to abut intermediate the ends of the jackets and means for securing the jackets on a spring.

55 6. A spring cover comprising detachable metallic jackets arranged in abutting relation, a lining for each jacket interconnected with one of the abutting jackets and means for detachably securing the jackets on a spring.

60 7. A spring cover comprising metallic jackets of graduated sizes arranged in abutting relation and a lining in each jacket tele-

scoping one of the jackets immediately adjacent.

8. A spring cover comprising metallic jackets of gradually decreasing cross section, said jackets being in graduated sizes and arranged in abutting relation, a lining for each jacket adapted to telescope one of the adjacent jackets and means for detachably mounting the jackets on a spring. 70

9. A spring cover comprising metallic jackets of gradually decreasing cross section, the jackets being in graduated sizes arranged in abutting relation, a lining for each jacket adapted to telescope one of the jackets immediately adjacent, means for securing the linings in the jackets and means for removably securing the jackets on a spring. 75 80

10. A spring cover comprising metallic jackets of gradually decreasing cross section arranged in abutting relation, a lining for each jacket telescoping one of the jackets immediately adjacent and abutting the lining therein, means securing the linings to the jackets, means for fitting the lining to a spring, and means providing for ready removal and replacement of the jacket. 90

11. A spring cover comprising a metallic jacket formed of a plurality of longitudinally extending abutting sections each formed in two parts, and a lining secured to the parts of each section and forming a hinge therefor. 95

12. A spring cover comprising a metallic jacket formed of abutting sections, and a water proof lining interior of the jacket sealing the joints between the sections. 100

In testimony whereof I affix my signature.

MILTON TIBBETTS.
